UNITED STATES PATENT OFFICE.

WILLIAM E. PHELPS, OF ELMWOOD, ILLINOIS.

IMPROVEMENT IN COAL-CHUTES.

Specification forming part of Letters Patent No. 121,413, dated November 28, 1871.

To all whom it may concern:

Be it known that I, WILLIAM E. PHELPS, of Elmwood, in the county of Peoria and State of Illinois, have invented certain Improvements in Coal-Chutes, of which the following is a specification:

The nature of my invention relates to improvements in coal-dumping apparatus for delivering coal to locomotive-tenders on railways; and the invention consists in the combination, with a suitable box provided with a slanting bottom, of a pivoted apron with a screen bottom, and also another apron pivoted to its under side, for the purpose of carrying back the screenings, all as hereinafter fully described.

Figure 1 is a perspective view of my invention with the aprons folded up. Fig. 2 is a vertical sectional view with the aprons and doors in position for discharging coal. Fig. 3 is a side elevation of the door to the coal-box and fastenings.

A represents the frame of the machine. B represents a box, supported on the frame A and having an inclined bottom, B', as shown. C is a door, hung, by pivots at its upper end, in the deep side of the box B. D D are latches on the door C, engaging with catches d d and holding the door C closed when desired, and being released through the intervention of cords d' d' and lever d''. E is an apron or chute pivoted between the frame pieces A A just beneath the lower end of bottom B', so that it may be turned up, as shown at Fig. 1, or down, as shown at Fig. 2. The out-

er end of the apron E is pierced with slots e e e e, and provided with side pieces e' e'. G is an apron pivoted at one end to the outer end of the apron E, and extending back beneath the slats e e e e in the apron E, and supported at the desired angle by the cords or chains g g.

The operation of my invention is as follows: The door C being closed and secured by latches D the box B may be filled with the desired quantity of coal, the aprons E and G being folded up. The locomotive-tender then coming up alongside, the apron E may be dropped so as to extend into its interior. The door C now being opened the coal will be led by the apron E into the tender, the finer portion dropping through the slots e e e e and being carried back by the apron G, on which they fall, away from the tender and out of the way. The coal from the box B being discharged, the aprons may be again folded up and the tender moved away. Weights I may be placed on the inner end of the apron E to balance it when free from coal, and to render it somewhat easier operated.

I claim as my invention—

The aprons E and G, constructed as described, in combination with the box B and door C, arranged to operate substantially as and for the purpose set forth.

WILLIAM E. PHELPS.
